REX TYPEWRITER COMPANY INCORPORATED, OF FOND DU LAC, WISCONSIN, A
CORPORATION OF VIRGINIA.

ESCAPEMENT MECHANISM FOR TYPEWRITING-MACHINES.

1,362,696.

Specification of Letters Patent. Patented Dec. 21, 1920.

Original application filed February 4, 1915, Serial No. 6,127. Divided and this application filed January 18, 1918. Serial No. 212,497.

To all whom it may concern:

Be it known that I, HUBERT K. HENRY, a citizen of the United States, and a resident of Detroit, county of Wayne, and State 5 of Michigan, have invented certain new and useful Improvements in Escapement Mechanism for Typewriting-Machines, of which the following is a specification.

The invention relates to escapement mechanism for typewriters and seeks to provide 10 a simple and effective escapement mechanism. A further object of the invention is to provide an escapement which is adapted for use on a front-strike typewriter having a vertically shifting carriage bed.

In the drawings: Figure 1 is a longitudinal section from front to rear of a typewriting machine with the present improvement applied thereto. Fig. 1^a is a detail view of parts shown in Fig. 1. Fig. 2 is a 20 partial longitudinal section with parts shown in shifted position. Fig. 3 is a partial rear elevation of the machine with the back plate removed. Fig. 4 is a view in elevation of 25 the escapement mechanism with parts shown in section on the line 4—4 of Fig. 1. Fig. 5 is a detail section on the line 5—5 of Fig. 4. Fig. 6 is a plan view of the carriage and carriage bed.

The machine frame comprises side plates 30 10 connected at their lower front and rear corners by the vertically disposed transverse plates 11 and 12 which are provided at their ends with the usual feet 13. The upper forward portions of the side plates 35 are connected by a vertically disposed transverse plate 14 and at a point somewhat in front of their rear ends the side plates are connected by a vertically disposed type-bar support or segment 15, each end of which 40 is fixed to one of the side plates by screws 16 (see Fig. 3).

The upper forward portion of the type-bar support is provided with a forwardly 45 projecting flange 17 which is provided with radial slots for receiving the rear ends of the type-bars 18, the latter being mounted upon a pivot rod 19. The type-bars are normally arranged in horizontal position 50 with the heads 20 at their forward ends resting upon a segmental support 21. The key levers 22 are provided with keys 23 at

their forward ends which are arranged in rows or banks at the front of the machine frame. The levers are pivotally mounted 55 intermediate their ends upon a series of pivot rods 24 arranged in horizontal series between the side plates 10, the key levers of each bank being mounted upon one of the pivot rods. The rear ends of the key 60 levers are connected to the type-bars to actuate the same by upwardly extending links 25. Light return springs 26 coiled about the pivot rods 24 engage the levers 22 and extend downwardly to a cross transverse 65 bar 27. A space-bar 28 is fixed to the forward ends of a pair of arms 29 which are mounted on one of the pivot rods 24 and are connected at their rear ends by an integral cross-bar 29'. The space bar is held 70 in normal position with a stop 30 thereon engaging a flange 31 on the front cross-bar 11 of the machine frame.

In the preferred construction shown, the paper carriage track or bed, the ribbon 75 mechanism and the escapement mechanism are all mounted on a vertically shifting frame so that any of the three sets of type carried by the type-bars can be brought to the printing point. The shift frame comprises uprights 32 at opposite sides of the machine, having forwardly and rearwardly projecting arms 33 and 34 at their upper ends. The forwardly projecting arms carry 80 the spool shafts 35 and casings 36 for the ribbon spools and the rearwardly projecting arms support the carriage track or bed 37. The rear edges of the uprights 32 abut 85 against the front face of the type-bar segment and the front edges thereof are engaged by adjustable guides 38 secured to the side plates 10. Guide-shoes 39 fixed to the rearwardly projecting arms 34 engage the inner faces of the side plates. The lower ends of the uprights engage a transverse rod 90 40 which is mounted upon the rear ends of a pair of arms 41, the forward ends of which are fixed to a rock shaft 42. Shaft 42 is journaled in side plates 10 of the machine frame and one of the arms 41 is provided 95 with a forwardly projecting extension 43 having a pair of shift keys 44 and 45 at its forward end. The shift frame and parts carried thereby are held in normal position 100

by gravity with stop pieces 46 (see Fig. 4) engaging the upper edges of the side plates 10. The weight of the shift frame and parts carried thereby is partially counterbalanced by one or more springs 47 (see Figs. 1 and 3).

The shift key 44 is fixed to the forward end of the extension 43 and the shift key 45 is mounted upon an arm 48 pivoted at 49 to the extension or lever 43 and having a depending lug 50. A spring 51 extending between the lever 43 and lug 50 normally holds the latter against a stop 52 on the lever. When the shift key 44 is depressed, the parts are arrested by the engagement of the short lever or key 48 with a stop-screw 53, and the carriage supporting frame and parts carried thereby are then raised to their highest position. When the shift key 45 is depressed, the carriage supporting frame is arrested in an intermediate position when the lug 50 engages a fixed lug 54 on the side of the machine frame.

The carriage track or bed is preferably formed of pressed sheet steel and provided at its front and rear edges with upwardly and inwardly inclined guide-flanges 55. The carriage is also preferably formed of pressed sheet steel and comprises a transverse bar or plate 56 which fits between the guide flanges 55 and is provided with down-turned and inwardly inclined flanges 57 which rest upon the carriage supporting bed plate 37. The plate 56 is also provided with upturned ends 58 which support the cylindrical platen 59, and a transverse rock shaft 60 arranged in the rear of the platen. A paper-feed table or plate 61 extends downwardly and forwardly in the rear of and beneath the platen, and is provided with ears 62 extending rearwardly therefrom and engaging the rock-shaft 60.

The carriage is propelled by a spring-drum 63 mounted in a bracket 64 on the underside of the carriage bed 37. The upper portion of the drum extends upwardly through an opening in the carriage bed and one end of a strap 65 is connected up and wound about the drum. The opposite end of the strap extends toward the right between the carriage and carriage track and is connected by a hook 66 (see Fig. 4) to the right-hand end of the carriage. The escapement which controls the letter-space movement of the carriage is preferably mounted upon the shifting frame and moves vertically therewith. For this purpose, a bracket 67, of inverted U-shape, is fixed to the under face of the carriage bed 37 and at the rear central portion thereof. This bracket has down-turned ears and also an upwardly and rearwardly projecting part 68 having at its upper end an inwardly offset stop-lug 69. A yoke 70 is connected to the bracket 67 by a horizontal pivot pin 71 and is provided with forwardly extending arms 72 which

support a pivoted dog-rocker. A bent or U-shaped arm 73 (see Fig. 1) is fixed to the yoke 70 and extends upwardly therefrom through an opening in the bracket 67. A spring 74, coiled about the pin 71, engages one of the arms 72 and holds the yoke 70 and parts carried thereby in normal position with the arm 73 engaging a stop-screw 75 which is adjustably threaded through the upright 68.

A dog-rocker 76, like the other parts of the escapement, is formed preferably of sheet metal and is T-shaped in outline, as most clearly shown in Fig. 4. The horizontal arms 77 at the upper end of the dog-rocker 80 are provided with pivot studs 78 at their ends which engage bearing openings in the forward ends of the arms 72. A pair of screws 79 and 80 are threaded through the upper portion of the dog-rocker, one above the other, and are provided with shouldered forward ends and threaded rear ends, the latter serving to secure a fixed dog 81 to the dog-rocker. A spacing dog 82 is pivotally mounted on the shouldered portion of the upper screw 79 and its lower end or tail is arranged between the upper ends of a pair of spring arms 83 and 84. The lower ends of the latter are integrally connected and are fastened to the lower end of the dog-rocker by a pivot screw 85. The springs 83 and 84 are adapted to bear upon the lower end or tail of the spacing dog 82 and also upon the shouldered front end of the screw 80.

The upper portion of the dog-rocker and the dogs thereon extend through an opening in the carriage bed or guide 37 into engagement with a rack-bar 86 fixed to the underside of the horizontal carriage plate 56. The spacing dog 82 normally engages the rack-teeth and the tension of the spring-drum 63 holds the spacing dog in the position shown in Fig. 4, with the dog against a stop lug 87 on the upper end of the dog-rocker 110 and with the spring 84 under tension. When the lower end of the dog-rocker is shifted rearwardly, as shown in Fig. 2, its upper portion is swung forwardly and the spacing dog 82 is moved out of engagement with the rack and the fixed dog 81 into engagement therewith. The spring 84 then swings the spacing dog 82 about its pivot so that, when the dog-rocker swings back, it will engage the next tooth of the rack and permit the 120 letter-space movement of the carriage. The shift of the spacing dog, effected by the spring finger 84, is limited by the spring-finger 83, but when the carriage is drawn back toward the right, the upper end of the spacing dog may be swung about its pivot toward the right against the tension of the spring 83. The spacing dog is also provided with a lug 88 which, while it permits the movements described of the spacing dog, co- 130

operates with the lug 87 to prevent the displacement of the dog.

It should be noted that the lugs 87 and 88 form rigid stops for limiting the movement 5 of the spacing dog about its pivot and the free upper ends of the spring arms or fingers 83 and 84 form oppositely acting, yielding stops for the pivoted spacing dog, while the front end of the screw or pin 80 limits 10 the action of the yielding spring-stops or fingers upon the spacing dog.

The lower end of the dog-rocker is connected to an actuating shifter 89 by a screw 90 which extends through a vertically slotted 15 part 91 of the shifter and through a forwardly turned lug on the lower end of the dog-rocker. The rear end of the shifter 89 is connected by a swinging link 92 to a lug 93 on the lower rear cross bar 12. The upper 20 front portion of the shifter is connected by a pivot pin 94 to a coupling member 95, and the latter is adjustably connected by screws 96 to the central portion of a universal bar 97. The latter is of segmental 25 form and extends above the type-bar segment in position to be struck by the type-bars when the latter are actuated, as shown in Fig. 2. At points adjacent its ends, the universal bar 97 is connected to the upper, 30 forwardly projecting ends of a pair of arms 98 which are arranged in the rear of the type-bar support of segment 15. Preferably the arms 98 and the universal bar 95 are formed of a single piece of pressed sheet steel. The 35 arms 98 are fixed at their lower ends to a rock shaft 99, the reduced ends of which are journaled in bearings 100, the latter being suitably mounted in the side plates 10. A spring 101 (see Fig. 3) is coiled about the 40 rock shaft 99, engages one of the arms 98 and holds the universal bar and the actuating shifter 89 in normal position with a stop-screw 102 in engagement with the rear face of the type-bar segment. This stop-screw is adjustably threaded through a lug 45 on the forward end of the shifter 89.

The universal bar and shifter are thus actuated by the key levers and type-bars to effect the dog-rocker to effect the letter-space movement of the carriage. The pin-and-slot connection between the dog-rocker and actuating shifter 89 permits the vertical shift of the dog-rocker with the carriage supporting frame. The link 92 serves to 55 maintain the slotted bars 91 substantially vertical as the universal bar is rocked rearwardly, so that the throw of the dog-rocker is substantially uniform in the different vertical positions of the carriage shift frame. 60 The shaft 99 is provided with a forwardly extending arm 103 which rests upon the rear cross-bar 29' of the arms 29, so that the space-bar 28 also serves to actuate the escapement dog-rocker. The arm 103 is bent 65 upwardly, as shown, so that it does not in-

terfere with the vertical shift of the bar or rod 40.

In the ordinary operation of the escapement, the dog-rocker oscillates in the yoke 70 and the latter is held stationary with the 70 upwardly projecting arm 73 in engagement with the stop-screw 75. By shifting the upper end of the arm 73 forwardly, the yoke 70 may be rocked upon the pivot pin 71 to depress the arms 72 and the dog-rocker carried thereby, and thus move the escapement dogs out of engagement with the carriage rack and permit the free lateral shift of the carriage. For this purpose the U-shaped 80 arm 73 is provided with an upwardly projecting portion 73' which extends behind and engages the rear face of a vertically disposed transverse rock-bar 104. This bar is provided at its ends with rearwardly turned lugs 105 that are fixed to the pivot 85 rod or rock shaft 60. By rocking the shaft the transverse rock bar 104 is oscillated and the upper end of the arm 73 is shifted forwardly to release the escapement. The engaging portions of the parts 73' and the bar 90 104 extend above and below rock shaft 60, so that the engagement of these parts tends to hold the bar 104 and shaft 60 in central position, and, by oscillating these parts in either direction from normal central position, the end of the arm 73 may be moved in forward direction to release the escapement. For shifting the pivot rod or rock shaft in opposite directions, a finger-piece 95 106 is fixed to the right-hand end thereof and preferably outside the right-hand end plate 58 of the carriage. The rock shaft 60 is journaled in rearwardly projecting portions or ears 107 on the carriage end plates 58 and the finger-piece 106 is provided with 100 inwardly projecting lugs 108 which are arranged in opposite sides of the adjacent ear 107 and serve to limit the movement of the release key and parts connected thereto, which, as described, can be shifted in opposite directions to release the carriage from 105 its escapement and the operator can then shift the carriage by hand to any desired position.

A stop supporting bar 109 extends between and is fixed to the rear ends of the lugs 105. A pair of margin stops 110 are adjustably mounted on this bar and are arranged to coöperate with the fixed stop lug 69 to limit the movement of the carriage in 115 opposite directions. One or more tabulator stops 111 are also adjustably mounted on the stop supporting bar or rod 109. The margin and tabulator stops are formed of sheet metal, bent to extend about the stop bar 109, 120 as most clearly shown in Fig. 1, and are adjustably held in position upon the rod by set-screws 112 or the like. The margin stops have rearwardly and downwardly projecting lugs 113 which are in position to 125 130

engage the fixed stop 69, whatever may be the position of the stop supporting bar 109, which, of course, oscillates with the rock shaft 60 and transverse bar 104.

5 The upper portion of each tabulator stop is provided with a rearwardly projecting lug 114 which, in the normal position of the stop-rod, passes over the upper end of the fixed stop 69, but by shifting the release key 10 106 rearwardly, the bar 109 and stops thereon will be lowered and the lug 114 of each tabulator stop brought in line with the fixed stop 69. At the same time the bar or plate 15 104 will be shifted to effect the release of the escapement and the carriage can then be moved by hand until the tabulator stop engages the fixed stop. By shifting the upper end of the finger-piece 106 forwardly, the carriage may be released without throwing 20 the tabulator stops into operation. Preferably, the screws 112 which hold the margin and tabulator stops in place are arranged to engage seats 115 formed in the upper edge 25 of the stop bar 109 at letter-space distances apart.

A combined ribbon vibrator and type-bar guide 116 is pivotally mounted between its ends upon a bracket 117 which is fixed to the front guide flange 55 of the carriage track. 30 The lower downwardly and rearwardly extending end portion of the ribbon vibrator is arranged to be engaged by an arm 118 which projects forwardly from the dog-rocker 76. In this way the combined ribbon 35 vibrator and type-bar guide is oscillated to and from the printing point by the escapement mechanism. The ribbon spools are mounted on shafts 35 in front of the platen and at opposite sides of the machine and 40 within the casings 36. Gears 119 are arranged to connect the spool shafts to a horizontal worm shaft 120. This shaft is journaled in the support 121 (see Fig. 3) which is shiftably mounted on the under side of 45 the carriage bed or track 37 so that worms 122 on opposite ends of the shafts can be alternately engaged with the gears 119 for driving the spool shafts. A ratchet wheel 123, centrally fixed to the worm-shaft, is arranged to be engaged by push-and-pull 50 pawls 124 and 125 which are pivoted on a lug or bracket 126 fixed to the escapement dog-rocker 76, and these pawls are connected by a spring 127 which holds them in operative 55 engagement with the ratchet wheel 123, so that the shaft is rotated as the escapement dog-rocker is oscillated. The escapement mechanism, ribbon vibrating and feed mechanism, as described, are all mounted on 60 the vertically shifting carriage supporting frame and are all properly operated by the universal bar and actuating shifter 89 in the different shifter positions of the carriage supporting frame.

65 It is obvious that changes may be made in

the details set forth without departure from the essentials of the invention as defined in the claims.

This application is a division of an earlier application for patent on improvements in 70 typewriting machines filed by me in the United States Patent Office February 4, 1915, Serial No. 6,127 patented January 22, 1918, No. 1,254,501.

I claim as my invention:

1. In a front-strike typewriter, the combination with a platen, platen carriage and upwardly and rearwardly striking type-bars, of a vertically shifting support for said carriage, an escapement mounted on said support and including a vertically disposed, swinging dog-rocker, a horizontally shifting universal bar coöperating with said type-bars, swinging rock arms pivotally mounted at their lower ends and connected at their upper ends to said universal bar, an actuating member interposed between said universal bar and said dog-rocker and means coöperating with said actuator for maintaining the throw imparted to said dog-rocker uniform in the different positions of said vertically shifting support. 90

2. In a front-strike typewriter, the combination of a platen, platen carriage and upwardly and rearwardly striking type-bars, of a vertically shifting support for said carriage, a horizontally shifting universal bar coöperating with said type-bars, supporting arms for said universal bar depending therefrom and pivotally mounted 100 at their lower ends, an escapement for said carriage including a vertically swinging dog-rocker pivotally mounted on said shifting support, an actuator connected to said universal bar and having a vertical slot 105 therein, said dog-rocker having a pin engaging said slot and a parallel movement, guide link for said actuator.

3. In a front-strike typewriter, the combination with a platen, platen carriage and upwardly and rearwardly striking type-bars, of a vertically shifting frame comprising uprights and a carriage bed fixed to said uprights, a rack fixed to the under side of said carriage, a vertical swinging dog-rocker pivoted on the under side of said carriage bed, dogs on said rocker extending upwardly through an opening in said bed, into engagement with said rack, a segmental universal bar coöperating with said 115 type-bars and arranged in front of the lower end of said dog-rocker, supporting arms for said universal bar depending therefrom and pivotally mounted at their lower ends, and connections between said 120 universal bar and said dog-rocker arranged to permit the vertical movement of the latter with said carriage bed.

4. In a front-strike typewriter, the combination with a platen and upwardly and 125

- rearwardly striking type-bars, of a vertically disposed type-bar support having a forwardly projecting slotted segment at its upper portion wherein said type-bars are pivoted, a segmental universal bar arranged above said segment, a rock shaft journaled in the lower portion of the machine frame in rear of said segment, supporting arms projecting upwardly from said rock shaft, 10 said universal bar being connected to the upper ends of said supporting arms and an escapement actuated by said universal bar.
5. In a typewriting machine, the combination with the carriage, carriage bed and propelling means for said carriage, of an escapement rack connected to said carriage, a vertically disposed dog rocker pivotally mounted on said carriage bed, fixed and 20 pivoted escapement dogs mounted on said rocker and projecting upwardly through an opening in said bed into engagement with said rack, said rocker and said pivoted dog having coöperating rigid stops for limiting the movement of the latter upon its 25 pivot, and said pivoted dog having a depending tail or lug, a pair of substantially parallel spring-arms pivoted at their lower ends to said dog rocker and having free upper ends engaging and oppositely acting
- upon the tail or lug of said pivoted dog, and a pin fixed to said dog rocker and arranged between the free upper ends of said spring-arms for limiting the action of said arms upon said pivoted dog, substantially 35 as described.
6. In a typewriting machine, the combination with a carriage and carriage bed, of an escapement rack connected to the carriage, coöperating escapement dogs, a 40 rocker whereon said dogs are mounted, a normally stationary, vertically movable support for said rocker mounted on the carriage bed and spring-held in normal position, and means on the carriage for shifting said support to disengage said dogs from said rack.
7. In a typewriter, the combination with a carriage and carriage bed, of a rack connected to the carriage, coöperating escapement dogs, a vertically movable support pivotally mounted on the carriage bed and normally spring-held against relative movement, a rocker for carrying said dogs pivotally mounted on said support, an arm on 50 said support and a shiftable release bar on said carriage arranged to engage said arm and depress said support to thereby disengage said dogs from said rack.

HUBERT K. HENRY.
